CLAIM

The ornamental design for a combined right angled fence post and cap, as shown.

DESCRIPTION

FIG. 1 illustrates a top view of a combined right angled fence post and cap of this invention.

FIG. 2 shows an enlarged fragmentary side view of the fence post of FIG. 4.

FIG. 3 illustrates a bottom view of the post and cap.

FIG. 4 shows an inside right hand view taken from a point on the inside of the property line.

FIG. 5 illustrates an outside view of the post of FIG. 4.

FIG. 6 illustrates an outside view of the post of FIG. 7.

FIG. 7 illustrates an inside left hand view taken from a point on the inside of the property line.
